(57) **CLAIM**

The ornamental design for an over the cabinet door styling rack, as shown and described.

DESCRIPTION

FIG. 1 is a perspective view of an over the cabinet door styling rack showing our new design;

FIG. 2 is a front view of the over the cabinet door styling rack; FIG. 3 is a side view of over the cabinet door styling rack, the opposite side view being a mirror image thereof.

FIG. 4 is a rear view of the over the cabinet door styling rack; FIG. 5 is a top view of the over the cabinet door styling rack; and,

FIG. 6 is a bottom view of the over the cabinet door styling rack.

The broken lines in the drawing illustrate environmental matter and form no part of the claimed design.
